UNITED STATES PATENT OFFICE.

JOHN M. PAGNOUL, OF BRIDGETON, NEW JERSEY.

DEVICE FOR CHARGING FURNACES.

SPECIFICATION forming part of Letters Patent No. 429,200, dated June 3, 1890.

Application filed March 13, 1890. Serial No. 343,716. (No model.)

To all whom it may concern:

Be it known that I, JOHN M. PAGNOUL, a subject of the King of the Belgians, residing at Bridgeton, county of Cumberland, State of New Jersey, have invented a certain new and useful Device for Charging Glass-Furnaces, of which the following is a true and exact description, reference being had to the accompanying drawings, which form a part of this specification.

10 My invention relates to devices by which the charge of batch is inserted into a tank glass-furnace.

Heretofore, so far as I am aware, the batch 15 has been simply dumped through the charge hole or door of the furnace, and the workmen in charging the furnace were compelled to come close to the open door, where they were subjected to the intense heat issuing from it.

20 My object is to enable the batch to be dumped into the furnace at a point well within the same and without requiring the workmen to approach very close to the open charging-door; and the leading feature of my invention 25 consists in combining with a truck a beam having a projecting end adapted to enter the charging-door of the furnace, a dumping-box secured on the end of this beam, and means for discharging said box when within the 30 furnace.

The construction of my device will be best 35 understood as described in connection with the drawings in which it is illustrated, and the novel features which I desire to protect by Letters Patent are hereinafter clearly pointed out in the claims.

In the drawings, Figure 1 is an elevation 40 showing my device in its preferred form and in connection with the tank glass-furnace 45 partially illustrated in section. Fig. 2 is a cross-sectional view taken on the line $x-x$ of Fig. 1, looking away from the furnace. Fig. 3 is a side elevation of a modification of my device; Fig. 4, an end view of the brace or truss connecting the two beams shown in Fig. 3, and Fig. 5 a side elevation of still another modification of my device.

A is the tank glass-furnace; a, its charging-door.

50 B indicates tracks which are arranged in

the plane of the charging-door of the furnace and outside of the same, as shown.

C indicates a truck or carriage, the wheels c of which move upon the tracks B, and which supports a beam D, a portion of which (indicated by the letter D⁴) is arranged in line with the charging-door of the furnace and adapted to enter the said door. Preferably that portion of the beam which is supported directly upon the truck is made to roll upon 55 the same, resting in the groove of rolls J, (see Fig. 2;) but the beam may be attached to as well as supported on the truck, if desired.

Upon the end of the beam which is extended 60 toward the charging-door of the furnace I secure a dumping-box F in any convenient way, and I provide said box with connections or mechanism whereby it can be discharged of its load, and for which purpose, of course, any 65 of the well-known devices used in connection 70 with dumping-boxes may be used.

In the drawings I have illustrated a simple 75 device consisting of a shaft E, supported in bearings d d' upon the beam D, and to the end of which projecting beyond the end D⁴ 80 of the beam I secure the box F, while to the other end of said shaft I attach a handle e. The dumping-box is so secured to the shaft that it will normally remain in an upright 85 position, but can easily be turned over by the operator turning the shaft by means of its handle e. Where, as in Fig. 1, the beam which supports the charging-box rests upon a truck moving on tracks situated below the door of the furnace, the weight of the box on 90 the long projecting end D⁴ of the beam is counteracted by means of a counter-weight G, secured upon the opposite end of the beam. In this construction, which, by reason of its 95 simplicity, I prefer to use, the beam occupies a considerable amount of space upon the floor of the building in which the furnace is situated. Where this is objectionable the space occupied can be diminished by means of the modified constructions shown in Figs. 3 and 95 5, in both of which figures the track B is supported above the level of the top of the furnace.

In the construction indicated in Fig. 3 a beam (marked D') is supported by the truck C 100

and connected by means of a truss or brace D³ with a parallel beam D², arranged in line with the charging-door of the furnace, and to the end D⁴ of which, as in Fig. 1, the dumping-box F is secured. The truss or brace D³ in this construction must of course be strong and rigid, and can well be constructed as shown in the drawings, Figs. 3 and 4. The beam D' is made up of two angle-irons II II, secured together by rivets or blocks, and to the inside of which are riveted plates h h, to which plates two pairs of angle-irons h' and h² are secured, as shown, the beam D² being connected and supported by the lower ends of these angle-irons. In order to stiffen the brace or truss, cross-bars h³ may properly be riveted to it.

In the construction shown in Fig. 3, as in that shown in Fig. 1, a counter-weight G should be used to counterbalance the weight of the dumping-box.

In Fig. 5 I have shown a construction in which a beam C' rests upon the axles of the wheels c c and has depending from it links I I, which are attached to and support a beam D', said beam D' being connected with a beam D² by means of a brace or truss D³, as in Fig. 3. In this construction the beam C' rolls on the axles of the wheels which move upon the track, and has lugs c², which come in contact with the said axles and prevent further movement of the beam C' upon the same in one direction, while the links I serve a similar purpose when the apparatus is moved in the other direction. When constructed in this way, a counter-weight need not be used, and, if desired, the connection between the beam C' and the beam D' may be made by a single link or chain; and if so, if we lengthen beam D' and place a counter-weight on the off side of the single link or chain, the whole apparatus revolves around this point.

Having now described my invention, what I claim as new, and desire to secure by Letters Patent, is—

1. As a device for charging glass-furnaces, a truck, a beam supported on said truck and adapted to enter the charging-door of a glass-furnace, a dumping-box secured at the end 50 of the beam, and means for discharging said box of its load.

2. As a device for charging glass-furnaces, a truck, a beam supported on said truck and adapted to enter the charging-door of a glass-furnace, a shaft journaled and supported on 55 said beam, and a dumping-box attached to the end of said shaft.

3. In combination with a tank glass-furnace, tracks arranged outside of the same in 60 the plane of its charging-door, a truck moving on said tracks, a beam supported on said truck in line with the charging-door of the furnace, a dumping-box secured at the end of said beam, and means for discharging said 65 box.

4. In combination with a tank glass-furnace, tracks arranged outside of the same in the plane of its charging-door, a truck moving on said tracks, a beam supported on said 70 truck in line with the charging-door of the furnace, a dumping-box secured at the end of said beam, a counter-weight arranged to balance the weight of the loaded dumping-box, and means for discharging said box, all 75 substantially as and for the purpose specified.

5. In combination with a tank glass-furnace, tracks arranged below and in the plane of the charging-door of the furnace, a truck moving on said tracks, a beam D, supported 80 on said truck arranged in line with the charging-door, a dumping-box supported on the end of said beam extending toward the furnace, a counter-weight supported on the other end of said beam, and means for discharging 85 said box, all substantially as and for the purpose specified.

J. M. PAGNOUL.
